CLAIM

The ornamental design for a pair of goggle strap retainer clips, as shown and described.

DESCRIPTION

FIG. 1 is a right side elevation view of a single goggle strap retainer clip of the invention mounted on a typical sports helmet;

FIG. 2 is an enlarged side elevation view thereof shown as a mirror image of each other;

FIG. 3 is an enlarged front elevation view thereof shown as a mirror image of each other;

FIG. 4 is a rear elevation view thereof.

FIG. 5 is a top plan view thereof; and,

FIG. 6 is a bottom plan view thereof.

The broken lines showing a typical sports helmet are for environmental purposes only and form no part of the claimed design.
